DIVING MASK

Phillip R. Widolf, 888 Van Dyke,
Laguna Beach, Calif. 92651

Filed May 27, 1968, Ser. No. 12,103

Term of patent 14 years

Int. Cl. D21—03

U.S. Cl. D83—1

FIG. 2.

FIG. 3.

FIG. 5.

FIG. 7

FIG. 6.

FIGURE 1 is a prospective view illustrating the front, top and right side of the diving mask design;

FIGURE 2 is a front elevational view of the diving mask design;

FIGURE 3 is a left side elevational view of the diving mask design;

FIGURE 4 is a top plan view of the diving mask design;

FIGURE 5 is a bottom view of the diving mask design;

FIGURE 6 is a rear elevational view of the diving mask design; and

FIGURE 7 is a vertical section through the center of the diving mask design.

The dominant features of the design are shown in solid lines.

I claim:

The ornamental design for a diving mask, as shown and described.
